UNITED STATES PATENT OFFICE.

WILKINSON D. NEVILLE, OF BAY CITY, MICHIGAN, ASSIGNOR TO WALWORTH & NEVILLE MANUFACTURING COMPANY, OF BAY CITY, MICHIGAN, A CORPORATION OF MICHIGAN.

MACHINE FOR SHAPING CROSS-ARMS OF TELEGRAPH-POLES.

SPECIFICATION forming part of Letters Patent No. 696,255, dated March 25, 1902.

Application filed April 8, 1901. Serial No. 54,866. (No model.)

To all whom it may concern:

Be it known that I, WILKINSON D. NEVILLE, a citizen of the United States, residing at Bay City, in the county of Bay and State of Michigan, have invented certain new and useful Improvements in Machines for Shaping Cross-Arms of Telegraph-Poles, of which the following is a specification, reference being had therein to the accompanying drawings.

- 10 The invention relates generally to machines for shaping bars of wood, and more particularly to machines especially designed for shaping cross-arms for telegraph-poles. These cross-arms are formed from wooden bars substantially rectangular in cross-section, and the object of the shaping is to give sufficient curvature to the upper face of the bar to cause it to readily shed water, and thereby prevent rotting of the arm. As the arms are 15 mortised into the poles, it is necessary to leave a central portion square in cross-section, and as the arms vary in length the machine for shaping them must be provided with the requisite adjustments, so as to be 20 adapted for all the different sizes. Furthermore, as the life of the arm depends largely upon the smoothness of its surface it is necessary to provide a cutter which will not split or tear the wood in entering or leaving the cut. 25 It is the object of the invention to obtain a machine that will fulfil the conditions as above set forth.

The invention therefore consists in the peculiar construction of a machine comprising 30 feeding-rolls for the work, a pair of oppositely-revolving rotary cutters, and automatic means for throwing said cutters in or out of the path of the work, so as to shape the two portions of the bar upon opposite sides of the 35 square center.

The invention further consists in the mechanism employed for controlling the movement of said cutters in or out of the path of the work and, further, in the peculiar construction, arrangement, and combination of parts, as hereinafter described and claimed.

In the drawings, Figure 1 is a longitudinal section through the machine. Fig. 2 is a cross-section thereof on line xx , Fig. 1. Figs. 50 3 and 4 are diagrammatic views illustrating

the operation of the machine, and Fig. 5 is a perspective view of one of the cross-arms as shaped by the machine.

In a suitable framework A are mounted for continuous rotation a series of pairs of feed-rolls B. These rolls are continuously driven by any suitable mechanism. (Not shown.)

C and C' are two rotary cutters journaled upon cross-shafts D and D', arranged between two pairs of said feed-rolls. The shafts 60 D and D' are journaled in vertically-movable bearings E and E', secured to the frame of the machine and adapted to be moved by mechanism, as will be hereinafter set forth. These shafts are revolved in opposite directions by means of a drive connection, which, as shown in Fig. 1, comprises pulleys F and F' on said shafts and a belt G, passing over one of said pulleys and under the other, thence around an idler-pulley H and a drive-pulley I on the drive-shaft J. The relative arrangement of these pulleys and the drive-belt is such that the pulleys F and F' are free to move vertically with their respective shafts without interfering with the drive connection.

The shafts D and D' are normally held in positions to respectively place their cutters C and C' out of or in the path of the work fed between the rolls B. The bearings E for the shaft D must normally be held in their raised 80 position, and to this end the bearings are connected to a link K, which in turn is connected to a counterweighted lever L, the weight being sufficient to more than balance that of the shaft and cutter. The bearings E', on the other hand, are normally lowered and are connected by links K' to the counterweighted lever L', which is insufficient to balance the shaft and cutter.

M and M' are two dogs or trips arranged in 90 rear of the feed-rolls (or to the right hand, Fig. 1) and pivotally connected to the frame, so as to be longitudinally adjustable thereon. To form this adjustable pivotal connection, the frame is provided with a longitudinally-slotted bar N at one side of the path of the work, to which the dogs M and M' are adjustably secured by bolts O. Each dog is provided with an inclined face projecting into the path of the work, and the free ends of 95 100

said dogs are connected, respectively, by rods P and P' with rock-frames Q and Q', pivotally secured in the frame. The dog M is so fulcrumed that when its inclined face is depressed the rod P will be lowered, thereby rocking the frame Q downward. The dog M', on the other hand, is fulcrumed, so as to lift the rod P' when its inclined face is depressed, and thereby rock the frame Q' upward. The rock-frame Q is adapted, through the medium of the lever R, to lift the weighted lever L, and thereby allow the shaft D and cutter C thereon to be lowered. The frame Q' is also connected to the weighted lever L' by the lever R'; but the latter is so arranged that when the rock-frame Q' is swung upward the shaft D' and cutter C' thereon will be raised. The rods P and P' are so connected to the frames Q and Q' that when their respective dogs M and M' are adjusted longitudinally upon the frame said rods will also adjust themselves upon the frames Q and Q'. The connection, as shown, comprises a hook upon the rod P' and a fork upon the rod P, which embraces the longitudinal bars a' a on said frames.

The machine being constructed as above described, its operation is as follows: Motion is imparted to the shaft J and through the medium of the pulley I and belt G to the pulleys F and F'. The belt and pulleys are driven in the direction indicated by the arrows, Fig. 1—*i. e.*, the rear pulley F is driven to rotate its cutter in the direction in which the work is fed, while the pulley F' drives its cutter against the work. The operator taking his station at the forward end (to left-end side) of the machine feeds the square cross-arms successively into engagement with the feed-rolls B, suitable longitudinal guides (not shown) serving to center said arms in relation to the cutters. As the cutter C is normally out of the path of the work, the latter will pass underneath said cutter without being operated upon and will first come into engagement with the rear cutter C'. This will shape the upper face of the work, giving it the desired rounding form, and the operation will be continued until the end of the cross-arm 50 comes in contact with the inclined face of the dog or trip M. The further movement of the work will then rock said dog and through the medium of the link P, rock-frame Q, and the lever R will raise the weighted lever L and permit the shaft D to descend, carrying the cutter C into the work. The dog M is so adjusted in position that the cutter C will be thrown into the work just after the central square portion of the arm has passed said cutter, and when once in action it will continue to shape the arm to the end. After the cutter C is in action the cutter C' will also continue to operate upon the work for a short interval, and this is for the reason that the space between the two cutters is necessarily greater than the distance between the two shaped portions of the cross-arm. Before the perma-

nently square portion of the cross-arm reaches the cutter C' the forward end of said cross-arm will come into engagement with the inclined face of the dog M' and through the medium of the link P', rock-frame Q', and lever R' will depress the weighted lever L and through the link K' lift the shaft D', carrying the cutter C' out from the work. In being thus forced out of the work the cutter C' will not tear or roughen the work, for the reason that it is revolving in the direction of the arrow—*i. e.*, in the direction of travel of the work.

From the above description it will be understood that the cross-arms may be fed successively through the machine and in passing through each is shaped upon opposite sides of its center, while the central portion of each remains square to fit the mortise in the pole. Whenever it is desired to change the length of the arms, the machine may be readily adjusted by the simple operation of shifting the dogs M and M' to the proper position, while the rods P and P', on account of their sliding connection with the bars a' a and the frames Q and Q', will automatically adjust themselves.

While I have described my machine as designed for the specific purpose of shaping cross-arms for telegraph-poles, it is obvious that it may have other uses, and I do not desire to be limited to this one use.

What I claim as my invention is—

1. In a machine for shaping wood, the combination with longitudinal feed mechanism for the work, of a pair of rotary shaping-cutters movable into or out of the path of the work, one being held normally in and the other normally out, and dogs in rear of said cutters projecting into the path of the work and respectively adapted to change the position of their cutters, said dogs being located to be operated by the forward end of the work so as to cause the shaping of the two opposite end portions of said work leaving a central portion unshaped.

2. In a machine for shaping wood, the combination of a frame, longitudinal feed mechanism for the work and a shaping-cutter movable into or out of the path of said work, a pivotal dog located in rear of said cutter and longitudinally adjustably secured to said frame, a rock-frame secured to the stationary frame and having a longitudinally-extending bar, a rod connecting said pivotal dog with said rock-frame and longitudinally adjustable upon the latter to remain vertical in the different positions of adjustment of said trip, and an operating connection between said rock-frame and cutter whereby the movement of said dog will throw said cutter in or out of the work.

3. In a machine for shaping wood, the combination of a frame, longitudinal feed mechanism thereon for the work, a pair of rotary cutters arranged to operate upon the work one in advance of the other, dogs pivotally and longitudinally adjustably secured to said frame in rear of said cutters and projecting into the

path of the work, rock-frames pivoted to the frame below said dogs and having longitudinal bars, rods connecting said dogs and rock-frames adjustable upon the latter correspondingly to the adjustment of said dogs upon the frame, and connections between said rock-frames and cutters whereby one of the latter is normally held out and the other normally held into the work, and whereby their positions are changed by the engagement of the work with their respective dogs.

4. In a machine for shaping wood, the combination with longitudinal feed mechanism for the work, of a pair of shaping-cutters arranged to operate upon the work, one in advance of the other, the rear cutter being held normally in the path of the work, and the for-

ward cutter being held normally out of the work, a pair of dogs in rear of said cutters and projecting into the path of the work, and connections between said dogs and cutters whereby the forward dog will throw the forward cutter into the work after said rear cutter has been in operation and subsequently said rear dog will throw said rear cutter out of the work leaving a central unshaped portion of the work which is less in length than the distance between said cutters.

In testimony whereof I affix my signature in presence of two witnesses.

WILKINSON D. NEVILLE.
